A. C. BEAGLE.
GAS ENGINE VALVE GRINDER.
APPLICATION FILED MAY 11, 1916.

1,216,925.

Patented Feb. 20, 1917

UNITED STATES PATENT OFFICE.

ANDREW C. BEAGLE, OF BERWICK, PENNSYLVANIA.

GAS-ENGINE-VALVE GRINDER.

1,216,925.

Specification of Letters Patent. Patented Feb. 20, 1917.

Application filed May 11, 1916. Serial No. 96,847.

To all whom it may concern:

Be it known that I, ANDREW C. BEAGLE, a citizen of the United States, residing at Berwick, in the county of Columbia, State of Pennsylvania, have invented certain new and useful Improvements in Gas-Engine-Valve Grinders; and I do hereby declare the following to be a full, clear, and exact description of the invention, such as will enable others skilled in the art to which it appertains to make and use the same.

This invention relates to tools and more particularly to tools designed for use in grinding the valves and seats of gas engines of the usual puppet valve type and has for its object to provide a device of this kind by means of which the valves and seats may be simultaneously ground without removing the valves and stems or the valve springs.

Another object is to provide a device of this kind which may be easily and quickly applied.

In the drawings:

Figure 1 is a section taken through the exhaust outlet and adjacent parts of a gasoline motor, illustrating the use of the present invention.

Fig. 2 is a view showing only a fragment of the engine in section, and illustrating the act of placing the grinder in position.

Fig. 3 is an elevational view of the grinder.

Fig. 4 is a top plan of the grinder.

Fig. 5 is a section on line 5-5 of Fig. 4 showing the arrangement of the beveled faces at the opening of the grinder, in perspective.

Referring now to the drawings the present invention comprises an annular member 6 having its periphery and underface beveled as indicated at 7 to conform to the bevel of a valve seat indicated at A in Fig. 1. The upper surface of the annular member 6 is beveled downwardly and inwardly as indicated at 8 to conform to the bevel of a valve indicated at B in Fig. 1. It will be understood that these beveled surfaces 7 and 8 conform absolutely to each other so that when a valve is ground upon the surface 8 it will fit a seat ground by the surface 7.

At one point the annular member 6 is cut away as indicated at 9 to form a passage communicating with the inclosure of the annulus and opening through the outer surface of the member. This forms what will be termed an open annulus and by the term

"open annulus" it is to be understood that a structure having the just described formation is meant.

At the sides of the opening 9 the member 6 is beveled to produce downwardly converging surfaces 10 and 11. These beveled surfaces lie at the ends of the surface 8 so that there can be no cutting action during the operation of the grinder which would result if the ends of the surface 8 at the sides of the opening 9 were left sharp.

At a point diametrically opposite the opening 9, the member 6 is provided with an outwardly extending radial ear 12. An operating handle 13 is provided which consists of a short normally vertical stock 14 having a suitable grip 15 at its upper end. At the lower end of the stock 14 there is a laterally and downwardly inclined extension 16 having its lower end turned vertically and bifurcated as shown at 17 to embrace the ear 12 to which it is pivoted by means of a pin 18.

Pivoted to the handle 13 at the union of the stock 14 and the extension 16 there is an arm 19 which extends normally downwardly and laterally in true divergent relation to the extension 16, and this arm carries a lip 20 at its lower end arranged to engage within the opening 9 between the straight lower portions 21 of the faces which lie at the sides of this opening. A slight shoulder 22 is formed upon each of these faces 21 so as to be engaged by the under face of the lip 20.

In use, the valve stem and valve of a motor are raised in any suitable way against the action of the valve spring indicated at C in Fig. 1. The member 6 is then engaged between the valve and the valve seat, with the face 7 directed downwardly, it being understood that the opening 9 is of a width to permit the passage of the valve stem therethrough. During this operation, of course, the parts are in a position shown in Fig. 2. The operating handle is then moved upon the pivot pin 18 and the lip 20 is engaged in the opening 9. Oscillation of the grip 15 will then result in grinding of the valve and seat, it being understood that suitable grinding compound has been placed upon them.

During the operation of valve grinding it is of course important that the grinding surface be separated occasionally to prevent scarring. To accomplish this there may be

employed a valve lifter of the chain and lever type such as is illustrated in Fig. 1 and indicated at D. With such a lifter the operator may occasionally lift the valve 5 against the action of the spring C by foot pressure as illustrated. In engines employing powerful valve springs the lever may be engaged beneath the collar indicated at E as 10 illustrated in dotted lines in Fig. 1 so that the pressure of the spring may be reduced should this pressure be such as to interfere with the operation of the grinding tool.

What is claimed is:

1. A valve grinding tool comprising a body portion provided with a passage therethrough and having a valve receiving face at one side surrounding the passage and a valve seat engaging face at the opposite side surrounding the passage, the two faces being 15 formed to substantially conform to each other.
2. A valve grinding tool comprising a member having a passage formed therethrough and having a split communicating 20 with the passage and opening through the outer face of the member, said member having a valve receiving surface formed at one side and surrounding the passage and hav-

ing a valve seat engaging surface at the opposite side surrounding the passage.

3. A valve grinding tool comprising a member having a passage formed therethrough and having a split communicating with the passage and opening through the outer face of the member, said member having a valve receiving surface formed at one side and surrounding the passage and having a valve seat engaging surface at the opposite side surrounding the passage and a handle pivoted to the member at one side 35 and including an arm arranged for engagement in the opening.

4. A valve grinding tool comprising a grinding member provided with a stem receiving passage therethrough, and having a split 40 communicating with the stem receiving passage and opening through the outer face of the member, and a handle pivoted to the member and including an arm arranged for engagement in the split.

In testimony whereof, I affix my signature, in the presence of two witnesses.

ANDREW C. BEAGLE.
